UNITED STATES PATENT OFFICE.

MURRAY HENRY, OF SAN ANTONIO, TEXAS, ASSIGNOR OF ONE-EIGHTH TO R. C. SCARBOROUGH, OF SOUTH SAN ANTONIO, TEXAS.

BURNER.

1,331,431.

Specification of Letters Patent. Patented Feb. 17, 1920.

Application filed May 16, 1919. Serial No. 297,607.

To all whom it may concern:

Be it known that I, MURRAY HENRY, a citizen of the United States, and a resident of San Antonio, in the county of Bexar and 5 State of Texas, have invented new and useful Improvements in Burners, of which the following is a specification.

This invention relates to oil burners of the superheating type and has particular 10 references to that class of burners adapted to be used in connection with locomotives and other power units requiring the generation of steam as a propelling agent.

An important object of the invention is 15 to provide in a device of the above mentioned character a means whereby the oil or fuel employed may be sufficiently heated prior to its ejection therefrom to facilitate a complete combustion.

20 Another object of the invention is to provide in a device of the character described a means whereby steam or other fluid may be injected into and adequately mixed with the fuel simultaneously with the ejection of 25 the fuel from the device.

A further object of the invention is to 30 provide in a device of the above mentioned character a means whereby the fuel may be completely atomized upon its being released or ejected from the device as a whole.

35 A further object of the invention is to provide in a device of the above mentioned character a means whereby an auxiliary atomizing effect may be effected in connection with a prior atomizing of the main supply of fuel.

40 Other objects and advantages of the invention will be apparent during the course of the following description taken in connection with the accompanying drawings.

In the drawings, forming a part of this specification and wherein like numerals are employed to designate like parts throughout the same,

45 Figure 1 is a top plan view partly in section of the device embodying my invention,

Fig. 2 is a vertical longitudinal sectional view taken on line 2—2 of Fig. 1,

50 Fig. 3 is a vertical longitudinal sectional view taken on line 3—3 of Fig. 1,

Fig. 4 is a transverse sectional view taken on line 4—4 of Fig. 3,

Fig. 5 is a transverse sectional view taken on line 5—5 of Fig. 3, and,

Fig. 6 is a transverse sectional view taken 55 on line 6—6 of Fig. 3.

In the drawings, wherein for the purpose of illustration is shown a preferred form of my invention, the numeral 5 indicates a superheating chamber adapted to be located 60 within the fire box of a locomotive and suitably supported or retained therein by means of ears 6 provided with openings 7 adapted to receive bolts or other fastening instrumentalities. The superheating chamber 5, 65 as clearly shown in Fig. 6, comprises upper and lower walls 8 and side walls 9. Between the upper and lower walls 8 there is arranged a substantially U-shaped partition 10 terminating at its ends in proximity to 70 the forward end of the chamber 5 as clearly shown in Fig. 1. The partition 10, as is apparent, divides the heating chamber 5 into 75 sub-chambers 11 and 12—12. The sub-chamber 12 is maintained in communication with a liquid fuel conveying pipe 13 through an opening 14, clearly shown in Fig. 2. The liquid fuel conveying pipe 13 is adapted to be connected to a suitable source of supply 80 of liquid fuel, not shown. This source of fuel supply may be incorporated as a part of the present day locomotive tender if the device embodying my invention is used in connection with locomotives or it may be a stationary tank suitably located if the device 85 embodying my invention is used in connection with power plants of the stationary character such as those plants which are used for the production of heat, power, light, etc. The heating chamber 5, as 90 clearly shown in Fig. 1, is connected to a second chamber indicated as a whole by the numeral 15. This chamber is divided into sub-chambers 16, 17 and 18. The chambers 16 is maintained in communication with 95 both of the sub-chambers 12 as clearly shown in Fig. 3. The heated liquid passing from the heating chamber 5 follows the course shown by the arrows of Fig. 3 entering the chamber 16 whereupon it passes upwardly through an elongated opening 19 and upon escaping from the opening 19 is atomized and sprayed into the atmosphere directly over the heating chamber 5 as will hereinafter be more fully described. The 100 chamber 18 extends forwardly an appreciable distance and terminates in proximity to the opening 19 as clearly shown in Fig. 2.

90

95

100

105

The chamber 18 is supplied from a suitable source, not shown, with steam flowing in the direction indicated by the arrows therein of Fig. 2. A part of the steam entering the 5 chamber 18 is deflected through a narrow opening 20 directly beneath an elongated deflector 21 which is secured in position by means of bolts as shown at 22. The steam thus passing through the elongated opening 10 20 under pressure consequently atomizes the heated liquid fuel passing upwardly through and out of the elongated opening 19. The heated fuel when passing from the opening 19 is of a more or less foamy or 15 boiling nature, thus because of this condition not only does it make possible its being easily atomized or sprayed forwardly but it also facilitates its complete combustion. The steam acting under pressure as above described 20 serves not only to atomize the superheated liquid fuel but also as a means to facilitate complete combustion in that due to the intense heat of the burning liquid the molecules of steam are broken up into constituents of free oxygen and hydrogen, the oxygen serving to support combustion of the liquid fuel while the hydrogen burns with intense heat.

While the main portion of the heated fuel 30 is atomized upon its being ejected from the passage 19 there is, however, a limited quantity moved forwardly in an unatomized condition. As a means for atomizing this superfluous quantity which would otherwise 35 run down on to the upper side of the heating chamber 5 I employ the auxiliary chambers 17 which communicate with the chamber 18 as shown at 23. The chambers 17 extend longitudinally with the chambers 16 and 18 40 and communicate with a transversely arranged duct 24, the steam passing from the chambers 18 into the duct 24 in the direction of the arrows shown therein in Fig. 1. The duct 24 is partially closed by a head 25 similar to the deflector 21, it differing however, in that its construction permits the steam to escape above through an opening 26 rather than below as through the opening 20 hereinbefore described. It is apparent 45 from the above description that any unatomized liquid flowing over the upper wall of the duct 24 will drop upon the face of the head 25 whereupon a complete atomizing effect is produced by the steam escaping 50 from the duct 24 under pressure through the opening 26.

In use, liquid fuel is passed into the pipe 13 in the direction of the arrows therein whereupon it enters the chamber 11 through 60 opening 14. The liquid fuel upon entering the chamber 11 is heated by the flame of the burning liquid above the heated chamber 5. The liquid fuel passes out of the chamber 11 and into the chambers 12 in the direction of 65 the arrows therein as shown in Fig. 1. The

fuel upon entering chambers 12 passes backwardly entering the elongated opening 19 in a heated condition. The superheated fuel passes upwardly and out of the elongated opening 19 whereupon steam under pressure 70 passing from chamber 18 through the opening 20 is brought into contact with the heated liquid in a foamy condition. As a result of the contact of the steam under pressure with the heated fuel an atomizing effect 75 is produced whereupon the major portion of the fuel is sprayed forwardly and burned with an intense heat. The intense heat is due partially to the heated condition of the liquid fuel which facilitates complete combustion and also to the ultimate breaking up 80 of the steam into its constituents of hydrogen and oxygen, the oxygen going to support combustion while the hydrogen burns with intense heat. A portion of the unatomized liquid is driven forwardly by the steam issuing from the opening 20 but this unatomized liquid is finally brought into contact with the steam issuing from the opening 26 under pressure whereupon a 85 complete atomizing effect of the total amount of fuel passed through the heated chamber 5 is produced.

It is to be understood that the form of my invention herewith shown and described is to be taken as a preferred example of the same, and that various changes in the shape, size and arrangement of parts may be resorted to without departing from the spirit of the invention or the scope of 95 the subjoined claims.

Having thus described my invention, what I claim as new and desire to secure and protect by Letters Patent of the United States, is:

105

1. A device of the character described comprising a liquid heating chamber, a U-shaped partition arranged therein to reverse the flow of liquid, means for directing the liquid from said chamber upwardly into the atmosphere, a second chamber adapted to receive steam under pressure, means for directing the steam from the second named chamber into contact with the upwardly directed liquid whereupon the liquid is atomized and impelled forwardly to be burned over the heating chamber, means for shunting a portion of the steam from the second named chamber into contact with a minor portion of the liquid fuel subsequent to the above mentioned contact of the steam with the liquid.

115

2. A device of the character described comprising a liquid heating chamber, a U-shaped partition arranged therein for reversing the flow of liquid, a liquid supply pipe communicating with the heating chamber between the walls of said U-shaped partition, means for directing the liquid upwardly from said heating chamber, a sec- 125

130

- ond chamber adapted to receive steam under pressure, means for directing steam from the second named chamber into contact with the liquid passed from the first 5 named chamber, a major portion of said liquid being impelled forward in an atomized condition to be burned directly over the heating chamber.
3. A device of the character described 10 comprising a liquid heating chamber, a U-shaped partition arranged therein for reversing the flow of liquid, a liquid supply pipe communicating with the heating chamber between the walls of said U-shaped partition, means for directing the liquid upwardly from said heating chamber, a second chamber adapted to receive steam under 15 pressure, means for directing steam from said chamber into contact with the liquid passed from said chamber, a major portion 20 of said liquid being impelled forward in an atomized condition to be burned directly over the heating chamber, and means for shunting a portion of the steam from the second named chamber whereby it is directed into contact with a minor portion of the liquid subsequent to its passage from 25 said heating chamber, the minor portion of the liquid being atomized and impelled forwardly over the heating chamber as a result of the contact of the shunted steam therewith.

MURRAY HENRY.
